UNITED STATES PATENT OFFICE.

MAX L. GORDON, OF LOS ANGELES, CALIFORNIA, ASSIGNOR OF ONE-HALF TO CHAS. E. PACKMAN, OF LOS ANGELES, CALIFORNIA.

SASH-FASTENER.

SPECIFICATION forming part of Letters Patent No. 763,879, dated June 28, 1904.

Application filed July 1, 1903. Serial No. 163,962. (No model.)

To all whom it may concern:

Be it known that I, MAX L. GORDON, a citizen of the United States, residing at Los Angeles, in the county of Los Angeles and State of California, have invented new and useful Improvements in Sash-Fasteners, of which the following is a specification.

My invention relates to new and useful improvements in sash-fasteners; and its object 10 is to provide a simple and inexpensive device which may be readily attached to a window-frame and which will securely lock a sash in any position to which it may be moved, thereby permitting sash balances and cords to be 15 dispensed with.

With the above and other objects in view the invention consists in the novel construction, combination, and arrangement of parts hereinafter more fully described, illustrated, 20 and claimed.

In the drawings, Figure 1 is an elevation of a portion of a window sash and frame, the same being broken away to show the sash-lock in elevation and to show the means for fastening the rack to the window-sash. Fig. 2 is an enlarged horizontal section through the sash-lock. Fig. 3 is an elevation of a portion of a window-frame having my improved sash-lock therein, and Fig. 4 is a vertical section 25 through the lock.

Referring to the figures by numerals of reference, 1 is a bar having V-shaped teeth 2 on the outer face thereof, and the ends of this bar are provided with arms 3, arranged at 30 right angles thereto. The bar 1 is adapted to be placed upon one side edge of a window-sash 4, and the arms of this bar overlap the ends of the sash and are secured thereto by means of screws 5 or other suitable fastening 35 devices. The inner surface of the window-frame 6 is slotted in alinement with the bar 1, as shown at 7, and secured within the frame adjacent this slot is a slotted plate 8, having horizontally-extending arms 9, connected 40 by a cross-strip 10. One of the arms 9 has a longitudinally-extending slot 11, through which extends a revoluble rod 12, which also projects through a slot 13, formed in the inner face of the window-frame 6. At the inner

end of rod 12 is arranged an arm 14, which 50 extends at right angles to said rod and projects through the slotted plate 8 and the slot 9, the inner end of this arm being tapered and normally engaging two of the teeth 2 on bar 1. A bow-spring 15 is riveted or otherwise 55 secured to the cross-strip 10, and the other end thereof is fastened in any suitable manner to a block 16, secured to the rod 12 in a plane at right angles to the arm 14. This spring serves to hold the rod 12 normally in 60 position in the front end of the slot 11, and the arm 14 is therefore normally in engagement with the teeth on the rod 1. A suitable cap 17 is secured to the inner face of the window-frame 6 and forms a bearing for rod 12. 65 A lever 18 is arranged at the outer end of rod 12, as shown.

When it is desired to lower the window-sash 4, the lever 18 is moved in the direction of the arrow shown in Fig. 3, and the arm 14 70 is thus swung downward out of the path of the teeth 2. The sash can then be lowered, and when it is desired to lock the same the lever 18 is released and is promptly thrown backward into horizontal or normal position 75 by spring 15, and thereby reengages the teeth 2 and holds the sash. When it is desired to raise the sash, lever 18 is turned in the opposite direction, and the operation above described is then repeated. By slotting one of 80 the arms 9 the rod 12 and its arm 14 can be moved within the frame 6, so as to permit said arm to engage the teeth 2, even though the sash does not fit snugly within the frame 6.

The device is very simple and inexpensive 85 in construction and can be readily placed in position. The plate 8 can be fastened in the frame by means of screws 19 or in any other suitable manner.

In the foregoing description I have shown 90 the preferred form of my invention; but I do not limit myself thereto, as I am aware that modifications may be made therein without departing from the spirit or sacrificing the advantages thereof, and I therefore reserve the 95 right to make such changes and alterations as may fairly fall within the scope of my invention.

Having thus fully described my invention, what I claim as new, and desire to secure by Letters Patent, is—

The combination with a window-sash having a toothed rod secured to one edge thereof, and a slotted window-frame; of a slotted plate secured within the frame and adjacent the slot, arms extending from the frame, one of said arms having a slot therein, a cross-strip connecting the arms, a revoluble rod slidably mounted within one of the arms and extending from the frame, an arm at the inner end of the rod and projecting through the slot in

the arm, a block secured to the rod adjacent the arm, and a bow-spring permanently secured at opposite ends to the block and cross-strip, respectively, said spring serving to hold the arm normally in engagement with the toothed rod, and a lever secured to the revoluble rod.

In testimony whereof I affix my signature in presence of two witnesses.

MAX L. GORDON.
